US00D570337S

(12) **United States Design Patent** (10) **Patent No.:** **US D570,337 S**
Oliver (45) **Date of Patent:** **** Jun. 3, 2008**

(54) **BROKEN-LOOP RFID READER ANTENNA FOR NEAR FIELD AND FAR FIELD UHF RFID TAGS**

(75) Inventor: **Ronald A. Oliver**, Seattle, WA (US)

(73) Assignee: **Impinj, Inc.**, Seattle, WA (US)

(**) Term: **14 Years**

(21) Appl. No.: **29/265,163**

(22) Filed: **Aug. 25, 2006**

(51) **LOC (8) Cl.** **14-03**

(52) **U.S. Cl.** **D14/230; D14/233**

(58) **Field of Classification Search** **D14/138, D14/230-238, 299, 358; D12/42, 43; 343/700 MS, 343/700 R-705, 711-713, 741, 748, 767, 343/795, 819, 840, 846, 866, 871-908; 455/90.2, 455/90.3, 91, 128, 269, 344, 347, 562.1**

See application file for complete search history.

(57) **CLAIM**

The ornamental design for a broken-loop RFID reader antenna for near field and far field UHF RFID tags, as shown.

DESCRIPTION

The FIGURE is a top plan view of a broken-loop RFID reader antenna for near field and far field UHF RFID tags showing my new design. It is understood that the broken line segments in the drawing form part of the claimed design.
